UNITED STATES PATENT OFFICE

JOSEPH C. TURNER, OF OKLAHOMA CITY, OKLAHOMA

ROLLER SKATE

Application filed March 6, 1931. Serial No. 520,605.

My invention relates to improvements in roller skates having ice skate action.

The principal objects of my invention are to provide a device of this character which is new, novel, practical, useful and of evident utility; which is strong, positive in action, durable and reliable; which consists of but few sturdy parts, is easily operated, cannot easily get out of order and is efficient for the 10 purposes for which it is intended; to provide a roller skate having a U-shaped housing for a plurality of rollers arranged in tandem or single file, said housing being rocker or bow-shaped so that only two of said rollers may 15 be in contact with the floor at one time; to provide a device in which the weight of the skater is supported on a single, narrow, curved surface formed of rollers in tandem analogous to the runner or blade of the rocker 20 type of ice skate; a device in which only a short section of said curved surface is in contact with the floor at any one instant, thus permitting the skater to change his direction and make sharp turns by merely leaning the 25 skate; to provide an adjustable brake for the front roller which is of especial use when skating backward as well as for bringing the skater to a stop when going forward; to provide a tip or point at the extreme front 30 end of the skate to serve the double purpose of causing frictional action by contact with the floor when the skate is held in a certain position and also provide a means for turning or spinning on the skate without moving forward or backward; to provide a roller skate 35 analogous to an ice skate which will permit the skater to take sharp corners at daring angles, which will glide smoothly and easily over the floor, which will permit racing 40 speed, stunting and fancy skating not now possible with the present four wheel skate.

With these and other objects in view as will more fully appear, my invention consists in the construction, novel features, and combination of parts hereinafter more fully described, pointed out in the claims hereto appended, and illustrated in the accompanying one-sheet drawing, of which,

Figure 1 is a side elevational view showing a fragment of the shoe; Fig. 2 is a bottom

view of the rollers and housing; Fig. 3 is a rear elevational view showing a fragment of the heel; Fig. 4 is a perspective view brake lever and brake roller housing; Fig. 5 is a section on the line 5—5 of Fig. 1 and Fig. 6 is a section on the line 6—6 of Fig. 1.

Like characters of reference designate like parts in all of the figures.

It is understood that various changes in the form, proportion, size, shape, weight and other details of construction, within the scope of my invention may be resorted to without departing from the spirit or broad principle of my invention and without sacrificing any of the advantages thereof, and it is further understood that the drawing 60 is to be interpreted as being illustrative and not restrictive.

In my improved roller skate, it will be evident that the weight of the skater is supported by a short section of the rocker or curved surface in contact with the floor at any one instant, and that this arrangement allows the 70 said skater to change his direction or make sharp turns, by merely leaning the skate. This is impossible with the present four wheel type of roller skate, as there is no so-called 75 fifth wheel means of guiding the skate, so that any appreciable change in direction can be made only by picking the skate up from the floor and setting it down in the new direction.

My front roller, or wheel, is fitted with an adjustable brake. The most important use of this feature is in skating backwards. When going in this direction, especially when skating on one foot, the common tendency is for the skate to get ahead of the point of balance of the body. The common method of 80 overcoming this tendency when skating on ice skates is to raise up on the point or toe of the 85 skate so that the teeth or the notches, with which most ice skates are provided, will engage in the ice and retard the motion of the skater. This same effect can be had on my 90 improved roller skate by raising up on the toe of the skate until the wheel or roller which is fitted with the brake comes in contact with the floor.

The tip, point or pivot which is provided at 95

the extreme front end of the skate is designed to serve two purposes. First, it is intended, in connection with the braked wheel, to simulate the action of the notches, or teeth, of the ice skate, in that it furnishes a means of slowing the speed of the skate by providing a positive contact with the floor and thus producing a greater friction between the skate and the floor than is provided by the free rollers. This is also similar in action to the teeth in the ice skates in that it provides a point of secure footing for the purpose of regaining or retaining the balance of the skater. For instance, if the skater becomes overbalanced and the skates are moving on the floor in such position that it is difficult to regain his balance, he may raise up on the tips of the skates and obtain a firm footing on the floor. Second, these tips or pivots provide a method of turning, or spinning, on the skate without the necessity of moving forward or backward. The tips are free to turn on an axis perpendicular to the floor, when the skates are held in the proper position, so that the skater may raise up on these tips and spin around.

Thus it can be seen that I provide an improved roller skate which will duplicate the speed and other desirable qualities of the high grade ice skate and permit the exhilarating sport of skating to be enjoyed in a climate and at a time now forbidden to thousands of enthusiasts.

One embodiment of my invention is shown as follows: As illustrated in the drawing my device is rigidly attached to shoe 1, although it may be made to be detachably clamped to the shoe. I provide toe plate 2, and heel plate 3 for attaching to heel 4. Rivets 5 and 6 secure said plates 2 and 3 respectively to shoe 1. Inverted U-shaped frame 7 provides a rigid housing for the rollers. Plate 2 is connected to frame 7 by member 8 and plate 3 to said frame 7 by member 9. The forward end 10 of frame 7 is turned back under plate 2 and secured thereto by rivet 11. Adjacent the extreme end of member 10 I secure adjusting screw and nut 12 for applying the proper pressure to brake roller 24. Frame 7, as can best be seen in Fig. 1, has rocker or bow-shaped lower edges and forms a housing for rollers 13 to 20 inclusive, pivoted at a uniform distance from said edges. All of said rollers are free to move on ball bearings 34 except 20, the movement of which is regulated and retarded by brake roller 24. The curvature of the said frame 7 and the mounting of the rollers is such that only two of said rollers are in contact with the floor at any one time, for example 15 and 16 as shown in Fig. 1. The rollers being narrow and having small treads, and being placed in tandem or single file, provide a contacting surface with the floor analogous with the steel runners of ice skates in contact with the surface

of the ice. Sharp turns and other maneuvers can be made as readily with my roller skate on a floor as with the best style of ice skates on ice. Brake lever 21 is attached to connecting member 8 by pivot pin 22 through holes 23 of said lever 21. Brake roller 24 is housed in end 25 of lever 21 and turns on bolt pivot 26 screwed into hole 27. Adjusting screw 12 is seated in slot 28 of lever 21 and the nut of said bolt 12 provides means for applying the proper brake pressure to brake roller 24 and skate roller 20. When the skater wishes to slow up gradually he tips the skate forward until rollers 19 and 20 contact the floor when the brake action on roller 20 will stop him. The principal use however, of this braking action of roller 20, as already explained, is to prevent the skater from being overbalanced when skating backwards, as without the retarding effect of the brake the skate will shoot out from under him.

Immediately ahead of roller 20 I provide tip, point or pivot 29 of fiber or other suitable material, set in a short, rotating, cylindrical housing 30, secured to frame 7 by bolt and nut 31. The action and purpose of this point or pivot 29 and rotating housing 30 has been fully explained hereinbefore. The renewable treads 32 of the rollers may be of fiber or other suitable material, attached to rim 33 by any suitable means. Ball bearings 34 lessen friction and spacer sleeves 35 serve to keep the rollers centrally alined within the U frame 7. Bolt pivots 36 pass through one side of said U frame and are threaded into the other side of said U frame and form a rigid, substantial mounting for the rollers.

Having thus described my invention, what I claim as new and wish to secure by Letters Patent is:

1. A device of the class described, comprising a U-shaped housing for a plurality of rollers, a plurality of rollers pivoted within said housing and alined in tandem or single file therein to simulate the shape and action of the steel runner of an ice skate, toe plate, heel plate and connecting means for attaching said housing to a shoe, said housing having rocker or bow-shaped lower edges, the curvature of said lower edges being such that only two of said rollers are in contact with the floor at any one time, thereby permitting quick turns and sudden changes of direction of the skater, a front roller retarded by a brake, adjustable brake means for said front roller, said brake controlled roller being adapted to retard the skater, especially when skating backwards, and prevent overbalancing of said skater.

2. In a device of the class described, in combination, a U-shaped housing frame adapted to be attached to a shoe by any suitable means, a plurality of rollers pivoted within said housing in tandem or single file,

said housing having its lower edges formed in rocker or bow shape so that only two of said rollers are in contact with the floor at any one time, means thus provided whereby the weight of the skater is supported on a single, narrow, curved surface formed of said tandem rollers analogous to the runner or blade of the rocker type of ice skate, and adjustable roller brake means for the front roller.

10 3. In a device of the class described, in combination, a U-shaped housing frame adapted to be attached to a shoe by any suitable means, a plurality of rollers pivoted within said housing in tandem or single file, said housing having its lower edges formed in rocker or bow-shape so that only two of said rollers are in contact with the floor at any one time, means thus provided whereby the weight of the skater is supported on a single, narrow, curved surface formed of said tandem rollers analogous to the runner or blade of the rocker type of ice skate, adjustable roller brake means for the front roller, a point or pivot immediately ahead of said front roller,

20 23 said point being of fiber or other suitable material and renewable, a short, rotating, cylindrical housing for said point, means for attaching said cylindrical housing to said frame, said point and housing providing

25 30 positive frictional means with the floor for stopping the skater, said members also providing means whereby said skater can turn or spin without moving forward or backward.

4. In a device of the class described, tandem rollers in arcuate conformation, an adjustable brake for the foremost of said rollers and a frictional brake and pivot point in front of said foremost roller.
